(No Model.)

H. WITHEY.
SLIDING GATE.

No. 508,666.

Patented Nov. 14, 1893.

UNITED STATES PATENT OFFICE.

HENRY WITHEY, OF HASTINGS, MICHIGAN.

SLIDING GATE.

SPECIFICATION forming part of Letters Patent No. 508,666, dated November 14, 1893.

Application filed May 29, 1893. Serial No. 475,880. (No model.)

To all whom it may concern:

Be it known that I, HENRY WITHEY, a citizen of the United States, residing at Hastings, in the county of Barry and State of Michigan, have invented certain new and useful Improvements in Sliding Gates; and I do hereby declare the following to be a full, clear, and exact description of the invention, such as will enable others skilled in the art to which it appertains to make and use the same.

My present invention relates to certain new and useful improvements in gates, and is in the nature of an improvement upon the gate for which Letters Patent of the United States were granted to me on the 15th day of September, 1891, numbered 459,472; and to this end consists in the novel construction and arrangement of parts which I shall herein-after fully describe and afterward definitely point out in the claims, due reference being had to the accompanying drawings forming a part of this specification, wherein—

Figure 1 is a perspective view of my improved gate, showing the same open. Fig. 2 is a detail view of one of the supporting rollers for the gate. Fig. 3 is a vertical section taken through the gate post. Fig. 4 is a detail view of the means for adjusting the guide rollers upon the post. Fig. 5 is a detail view illustrating the manner of connecting the operating levers to the gate operating mechanism. Fig. 6 is a top plan view of the roller shown in Fig. 2.

Referring to the drawings A, A', indicate two posts and B a double post situated centrally between the posts A, A'.

C indicates the gate, which may be constructed in any suitable or preferred manner, and is of a length sufficient to reach from one of the posts A, A', to the central post B. Said gate is supported by and slides upon rollers, to be hereinafter described, and is operated by means of a lever D which at one end is pivoted to the post B and at its other end extends between two rollers e, e, journaled in a bracket E on the top panel of the gate. To the lever D is connected a rod d, which at its upper end is loosely connected to two links F, F, that are pivotally connected to the inner ends of levers G, G, which are pivoted to arms g, g, secured to the post B, said levers G, G, extending parallel with the roadway upon each

side of the gate and provided with cords g', g', which depend within easy reach of an occupant of a vehicle, one on horse-back, or a 55 pedestrian.

So far as described no novelty is claimed for the device, the operation of which is as follows: Upon approaching the gate one of the cords g' is pulled downward which, through the medium of the lever G and rod d throws the lever D over to the other side of the post B, thus causing the gate to slide open. After the rider or pedestrian has passed through the gate he pulls upon the other cord g' causing the gate to slide back to its former position, in which position it is locked by the notched end d' of the lever D resting over one of the rollers e. In order that the gate may automatically slide back and forth after 70 its initial movement has been accomplished by hand, I arrange the guide roller H upon the central post B at a higher level than the guide rollers K, K, that support the ends of the gate, whereby the gate, after it has been 75 propelled a sufficient distance past said post, will automatically slide to its open or closed position by gravity, the rollers constituting an inclined plane.

I have found in practice that it is necessary to provide means for adjusting the height of the gate, especially in winter time when the ground is covered with snow and ice, or to compensate for the warping of the parts, and to this end provide the following means: 80 Instead of journaling the roller H directly to the post B I journal it in a bracket h secured to a vertical slat I, said slat being provided with elongated slots i, i, through which, and the post B, pass headed bolts J, J, provided 85 with thumb nuts j, j, by means of which the slat, and the roller H carried thereby, may be vertically adjusted upon the post B. To the top of the slat I is secured a bracket i' which embraces or overhangs the top of the gate 90 and serves to maintain the same in a true vertical position.

The rollers K, K, are also made vertically adjustable as follows: L, L, indicate rods or tubes which are driven in the ground opposite each other at the proper distances apart, or they may be secured in a foundation plank L', to which the posts may be also secured, as shown. M indicates a journal box or casing,

consisting of two uprights m, m' , provided at top and bottom with outwardly extending flanges m', m' , the uprights being perforated for the reception of the journals of the roller K, and 5 the flanges m', m' , being recessed or forked so as to embrace the rods L, L, between which the said journal box or casing may be raised and lowered, its height from the ground being regulated by means of blocks or wedges N 10 which are inserted under it, and the thickness of which determines the height of the roller above the ground.

It will be seen that the height of the gate may be very quickly and easily adjusted, and 15 that the relative heights of the rollers H and K, may also be very readily adjusted to afford an easy automatic movement to the gate.

Having described my invention, what I claim is—

20 1. The combination with a sliding gate, and mechanism for operating the same, of rollers for supporting the opposite ends of the gate and a central roller arranged midway between the two, said rollers being independently vertically adjustable, substantially as described and for the purpose specified.

25 2. The combination with a sliding gate, and

its operating mechanism, of vertically adjustable supporting rollers K journaled in uprights m, m' , provided with outwardly projecting forked flanges m', m' , adapted to engage guide rods L, L, substantially as described. 30

3. In a sliding gate, the combination with the gate proper, of the post B, and the slat I, the latter being adjustably secured to said 35 post by means of the slots i, i , in the slat, and the bolts J, said slat I also carrying the gate supporting roller H at the bottom, and the hook bracket j' at the top adapted to catch over the top slat of the gate and hold the gate 40 in position.

4. In a sliding gate, the combination with the gate proper, of the end posts A, A', the central post B, the vertically adjustable slat I carrying the supporting roller H, and the vertically adjustable rollers K between the end posts and the middle post B, substantially as 45 described.

In testimony whereof I affix my signature in presence of two witnesses.

HENRY WITHEY.

Witnesses:

PHILIP T. COLGROVE,
EDWIN D. MALLORY.
